UNITED STATES PATENT OFFICE.

ARTHUR E. RUST, OF PINE MEADOW, CONNECTICUT, ASSIGNOR OF ONE-HALF
TO SOLON R. RUST, OF SAME PLACE.

MECHANICAL MOVEMENT.

SPECIFICATION forming part of Letters Patent No. 256,382, dated April 11, 1882.

Application filed March 4, 1882. (No model.)

To all whom it may concern:

Be it known that I, ARTHUR E. RUST, of Pine Meadow, in the county of Litchfield and State of Connecticut, have invented a new Improvement in Mechanical Movements; and I do hereby declare the following, when taken in connection with accompanying drawings and the letters of reference marked thereon, to be a full, clear, and exact description of the same, and which said drawings constitute part of this specification, and represent, in—

Figure 1, a side view; Figs. 2 and 3, diagrams illustrating the operation.

This invention relates to an improvement in mechanism for converting reciprocating into rotary motion, the object being to produce two full rotary movements to each full reciprocating movement.

The device is applicable to steam-engines where a rapid revolution of the fly-wheel is desirable without a corresponding rapidity of movement of the piston, and is also applicable to other devices where a reciprocating movement is to be converted into a rotary motion and the rotary motion desired to be a rapid one; and the invention consists in the system of levers between the pitman which receives the reciprocating movement and the crank to which that movement is transferred, as shown in the accompanying illustration and more fully hereinafter described.

A represents the pitman, which for illustration may be considered a pitman in connection with a common steam-engine piston. It is not necessary in this specification to describe the mechanism of the engine, whereby the reciprocating movement of the piston is imparted to the pitman or connecting-rod A. Instead of being attached to the usual crank, it is attached to an arm, a, or it may be a wheel on a rock-shaft, B. The reciprocating movement imparted to the pitman is less than the full diameter of the circle which would be described by the point b where the pitman is attached—that is to say, it starts forward above the dead-line d, as seen in Fig. 1, and terminates on the opposite side at a corresponding point, e, also above the dead-line d, as seen in Fig. 2, so that the pitman imparts a vibratory motion to the arm or wheel to which it is attached—that is

to say, from the position in Fig. 1 to that in Fig. 2, and return.

C is the driving-shaft, to which the crank-wheel D is attached; E, the connecting-rod, which is hung to the crank D on a crank-pin, f, in the usual manner for attaching connecting-rods to crank-pins.

Midway between the rock-shaft B and the driving-shaft is a slide, h, arranged in horizontal guides i, in the usual manner for arranging a cross-head. To this slide a lever is hung, as at m, so as to swing in a plane parallel with the plane in which the cranks turn; it extends above the pivot to form an arm, n, to which the connecting-rod E is attached, as at l, and below to form a like arm, o.

From the rock-shaft B an arm, p, extends up at right angles to the arm a. To this arm p, at a point, r, one end of a connecting-rod, F, is hung, the other end hung to the lever n o and at its center of vibration. Diametrically opposite the arm p is an arm, s, and to that arm, at a point, t, distant from the center of motion the same as the point r, one end of a second connecting-rod, H, is hung, its other end hung to the arm o, as at u. These points of connection or joints are made in the usual manner of making joints of connecting-rods.

The operation of the invention is as follows: Supposing the reciprocating movement to be a common steam-engine, and starting from the position in Fig. 1, which is the most forward position of the piston, and the piston moving to the rear to its first quarter or half throw, as seen in Fig. 1, the arms p s will be turned to bring their respective points r t diametrically opposite each other in a horizontal line. This will throw the slide or point m to its extreme rear position, and the connecting-rod H will draw the lower end of the arm or point u to its extreme forward position, and which, through the connecting-rod E, will throw the crank or point f to its extreme rear position, or opposite point to which it started, and will have made one-half revolution of the driving-shaft, while the piston has moved but one-half its extent. The piston, continuing its movement, carries the point b to its opposite or extreme forward position, as seen in Fig. 2. This quarter movement, turning the arm a to the position b, brings

the point *t* up and the opposite point, *r*, down, and draws the slide or point *m* to its extreme rear position, throwing the point *u* forward and the point *l* rearward, which brings the crank 5 or point *f* back to its point of starting, while the piston has only traveled from one end of its cylinder to the other, or one-half of the reciprocating movement only has been performed. The piston returning, and when at 10 the third quarter of its movement, or one-half its return, the points are brought again to the position as seen in Fig. 3, and one-half the revolution of the point *f* has been made. Continuing to its other extreme and completing the 15 reciprocating movement, the parts are brought again to the position as seen in Fig. 1, and completes the second revolution of the driving-shaft or point *f*. Hence it will be seen that by one complete reciprocation two full revolutions have been produced.

The piston or power which imparts the reciprocating motion does not at any time come to a dead-point at either end of its stroke, because the extent of oscillation or vibration of 25 the point *b* is less than one-half a full circle.

Applied to a steam-engine this mechanism imparts to the driving-shaft two revolutions for each full reciprocation of the piston—a great advantage where rapid revolution of the driving-shaft is desirable. This illustration as applied to a steam-engine will be sufficient to enable those skilled in the art to which this invention pertains to apply it to other machinery where it is required to convert reciprocating 35 into rotary motion.

I have described the connections with the rock-shaft as made by arms; but it will be understood that this may be a wheel and the con-

necting-rods attached to the wheel instead of to arms. I therefore use the term "arms" in a general sense and as embracing all equivalents therefor.

I claim—

1. The herein-described mechanical movement, consisting of a rock-shaft to which a vibratory movement is imparted from a reciprocating power, a crank arranged for full revolution, a slide between said crank and rock-shaft carrying an arm hung thereto, so as to vibrate in a plane parallel with the plane in which the crank swings, with a connecting-rod from the said crank to one end of said arm, and a connecting-rod from the opposite end of said arm to an arm extending from said rock-shaft, and a connecting-rod from an arm extending in the opposite direction from said rock-shaft to the center of motion of the arm to which the crank connecting rod is attached, substantially as described.

2. The herein-described method for converting reciprocating into rotary motion, consisting of a rock-shaft to which a reciprocating movement imparts oscillation less than half of a full revolution, with a shaft having a crank thereon arranged for full revolution, and an intermediate mechanism, substantially such as described, whereby the rotation or oscillation of the rock-shaft in one direction imparts a full revolution to the crank, and on its return imparts a second revolution to the crank, substantially as described.
